ABSTRACT: A noise and vibration-attenuating hanger which includes a resilient element intermediate upper and lower rigid plates, an overhead hanger engaging the lower plate and extending upwardly adjacent two opposite sidewalls of the resilient element and a depending hanger engaging the upper plate and extending downwardly adjacent two other opposite sidewalls of the resilient element, the said sidewalls of the resilient element tending to bulge outwardly under compression to push adjacent portions of the hangers outwardly and prevent the overhead hanger from engaging an edge of the lower plate and the depending hanger from engaging an edge of the upper plate which engagement would bridge the resilient element and nullify the effect thereof.

NOISE AND VIBRATION-ATTENUATING HANGER

This invention relates to a novel noise and vibration-attenuating hanger.

In one conventional vibration-attenuating hanger heretofore proposed, the hanger included a resilient element sandwiched between rigid plates, aligned holes through the plates and the resilient element, an upstanding hanger engaging the lower plate and extending upwardly through the holes and a depending hanger engaging the upper plate and extending downwardly through the holes. These prior art hangers are generally satisfactory, but the central hole through the resilient element reduces the load to which such hangers of a given size can be subjected and requires a larger resilient element than would otherwise be necessary.

In the noise and vibration-attenuating hanger of the present invention, an upstanding hanger extends upwardly adjacent a pair of opposite sidewalls of a resilient element interposed between upper and lower rigid plates and a depending hanger extends downwardly adjacent another pair of opposite sidewalls of the resilient element. In the preferred embodiment of the invention, the hangers are V-shaped and the resilient element is shaped so that one pair of the oppositely disposed sidewalls slope downwardly and inwardly from the upper to the lower surfaces of the resilient element and the other pair of oppositely disposed sidewalls slope downwardly and outwardly.

A feature of the vibration-attenuating hanger of the present invention is that the sidewalls of the resilient hanger tend to bulge outwardly when the resilient element is placed under compression. This tendency of the sidewalls to bulge urges that adjacent portions of the hangers outwardly so that the upstanding hanger is urged away from the edges of the upper rigid plate and the depending hanger is urged away from the edges of the lower plate. Such engagement would cause the hangers to bridge the plates and nullify the effect of the resilient element.

Another feature of the present invention is that the hangers frictionally engage the sidewalls of the resilient material so that the hanger elements will not become accidentally disassembled.

For a more complete understanding of the present invention, reference can be made to the detailed description which follows and to the accompanying drawing in which:

FIG. 1 is an exploded prospective view of the resilient element and the rigid plates which engage the upper and lower surfaces thereof;

FIG. 2 is a front elevation of the hanger;

FIG. 3 is a cross-sectional view taken along the line 3-3 of FIG. 2 looking in the direction of the arrows;

FIG. 4 is a perspective view of an alternative form of the hanger; and

FIG. 5 is a cross-sectional view taken along the line 5-5 of FIG. 4 looking in the direction of the arrows.

Referring to the drawing, the vibration-attenuating hanger includes a resilient element 10 interposed between upper and lower rigid plates 11 and 12, respectively, an upstanding hanger 13 engaging the lower plate 12 and extending upwardly and a depending hanger 14 engaging the upper plate 11 and extending downwardly. The hanger can be used, for example, for hanging heavy objects from a ceiling.

The resilient element 10 is preferably a solid block of an elastomeric material capable of attenuating vibration and noise. Neoprene is a suitable material which not only has these properties, but in addition has long aging properties, resistance to chemicals and oil and stability over a wide temperature range.

The hangers are preferably steel wires which are zinc plated or galvanized to resist wear and corrosion and bent generally in the shape of a V. The upstanding ends 13a of the hanger 13 engage aligned holes 15 and 16 in the bottom plate 12 and in the bottom of the resilient element 10. The hanger 13 extends

outwardly below and in engagement with the bottom plate 12 and then upwardly adjacent the sidewalls 22 of the resilient element in the form of an inverted V. Similarly, the ends of the depending hanger 14 engage aligned holes 17 and 18 in the upper plate 11 and in the upper surface of the resilient element 10. The hanger extends outwardly across the top of the upper plate 11 and then downwardly adjacent different sidewalls 19 of the resilient element in the form of a V.

The pair of opposite sidewalls 19 slope downwardly and inwardly from the upper surface 20 to the lower surface 21 of the resilient element to conform to the shape of the hanger 14. The other pair of opposite sidewalls 22 slope downwardly and outwardly from the upper surface 20 to the lower surface 21 to conform to the shape of the upstanding hanger 13. The upper and lower surfaces 20 and 21, respectively, of the resilient block are rectangular in shape with their longer dimensions oriented at right angles to each other.

The hangers frictionally engage the sidewalls of the resilient element so that they will not become accidentally disassembled from the resilient element while they are in storage or in shipment.

In the alternative embodiment of the hanger illustrated in FIGS. 4 and 5, the resilient element 10 contains slots 23 in the upper and lower surfaces to receive the ends of the hangers, and the upper and lower rigid plates 11 and 12, respectively, have aligned slots 24 therein. Also, the sidewalls of the resilient element contain grooves 25 to receive the adjacent portions of the hangers therein.

The smaller dimensions of the upper and lower rigid plates 11 and 12, respectively, are slightly less than the corresponding dimensions of the surfaces of the resilient element which they engage, so that the upstanding hanger 13 will not engage the upper plate 11 and the depending hanger 14 will not engage the lower plate 12. Obviously, if either hanger were to bridge both plates, the hanger would nullify the effect of the resilient element. Such bridging should not occur in the hanger because as the load increases the compressing effect on the resilient element will tend to bulge the sidewalls thereof and urge the adjacent portions of the hangers outwardly away from the edges of the plates.

The invention has been shown in preferred forms and by way of example only, and obviously various modifications may be made therein without departing from the spirit of the invention. The invention, therefore, should not be limited to any specified form or embodiment except insofar as such limitations are expressly set forth in the claims.

I claim:

1. A noise and vibration-attenuating hanger comprising a resilient element having upper and lower surfaces and at least two pairs of oppositely disposed side surfaces, rigid plates in engagement with the upper and lower surfaces, an overhead hanger engaging the lower plate and extending upwardly adjacent two of the oppositely disposed side surfaces and a depending hanger engaging the upper plate and extending downwardly adjacent two other oppositely disposed side surfaces, the said side surfaces of the resilient element tending to bulge under compression to push adjacent portions of the hangers outwardly and prevent the overhead hanger from engaging the upper plate and the depending hanger from engaging the lower plate.

2. A noise and vibration attenuating hanger as set forth in claim 1 in which the hangers are V-shaped and in which one pair of the side surfaces of the resilient element slope downwardly and outwardly from said upper surface to said lower surface and the other pair slope downwardly and inwardly from the upper surface to the lower surface.

3. A noise and vibration-attenuating hanger as set forth in claim 2 in which the upper and lower surfaces are substantially parallel and rectangular in shape with the longer dimensions thereof oriented at right angles to each other.

4. A noise and vibration-attenuating hanger as set forth in claim 3 in which the shorter dimensions of the plates are less than the shorter dimensions of the surfaces which they engage

to separate the upstanding hanger from the edges of the upper plate and the depending hanger from the edges of the lower plate.

5. A noise and vibration-attenuating hanger as set forth in claim 1 in which the upstanding hanger has a pair of upwardly extending ends and the depending hanger has a pair of depending ends and including means forming openings in the upper plate and the upper surface of the resilient element to receive the depending ends from the depending hanger and

means forming openings in the lower plate and in the lower surface of the resilient element to receive the upstanding ends of the upstanding hanger.

5. A noise and vibration-attenuating hanger as set forth in claim 5 including grooves in the side surfaces of the resilient element to receive and position the adjacent portions of the hanger.
